Primary Examiner — Philip S Hyder(74) *Attorney, Agent, or Firm* — Heslin Rothenberg Farley & Mesiti PC(57) **CLAIM**

The ornamental design for a trimmer as shown and described.

DESCRIPTION

FIG. 1 is a front, top perspective view of a trimmer comprising the new design;

FIG. 2 is a top view of the design of FIG. 1;

FIG. 3 is a back elevational view of the design of FIG. 1;

FIG. 4 is a front elevational view of the design of FIG. 1;

FIG. 5 is a left elevational view of the design of FIG. 1; and,

FIG. 6 is a right elevational view of the design of FIG. 1. The broken lines shown in the figures are directed to the environment and are for illustrative purposes only; the broken lines form no part of the claimed trimmer invention.
